POWERED RIDING LAWN MOWER

Orly Musgrave, Springfield, Ohio

Application November 9, 1954, Serial No. 33,039

Term of patent 14 years

(Cl. D40—1)

FIG.-1

FIG.-2

FIG.-3

FIG.-4

FIG.-5

Figure 1 is a left side elevational view of a powered riding lawn mower embodying my new design;

Figure 2 is a right side elevational view thereof;

Figure 3 is a plan view of the design of Figures 1 and 2;

Figure 4 is a front elevational view of the design of Figures 1-3; and

Figure 5 is a rear elevational view of the lawn mower.

I claim:

The ornamental design for a powered riding lawn mower, substantially as shown.
